(57) **CLAIM**

The ornamental design for a large collector for food, as shown and described.

DESCRIPTION

FIG. 1 is a front side perspective view of the large collector for food of the present invention;

FIG. 2 is a top view of the large collector for food of the present invention;

FIG. 3 is a left side view of the large collector for food of the present invention;

FIG. 4 is a right side view of the large collector for food of the present invention;

FIG. 5 is a back view of the large collector for food of the present invention;

FIG. 6 is a front view of the large collector for food of the present invention;

FIG. 7 is a bottom perspective view of the large collector for food of the present invention; and,

FIG. 8 is a bottom view of the large collector for food of the present invention.

The broken lines showing portions of the article form no part of the claimed design.

1 Claim, 6 Drawing Sheets
